SELF-PROPELLED WINDROWER

Cecil L. Case, 415 E. 8th St., Newton, Kans. 67114, and
Richard E. Ten Eyck, 7400 S. Seneca, Wichita, Kans.
67217

Filed June 29, 1967, Ser. No. 7,648

Term of patent 14 years

(Cl. D40—1)

Fig.1.

Fig.2.

Fig. 3.

Fig. 4.

Fig. 5.

Fig. 6.

FIGURE 1 is a side perspective view of a self-propelled windrower;

FIG. 2 is a perspective view of the side opposite to the side shown in FIG. 1;

FIG. 3 is a front perspective view;

FIG. 4 is a rear perspective view;

FIG. 5 is a top rear perspective view; and

FIG. 6 is a top front perspective view.

The dominant features of our design reside in the portions shown in full lines.

We claim:

The ornamental design for a self-propelled windrower, as shown and described.
